UNITED STATES PATENT OFFICE.

CHARLES B. DUDLEY AND JOHN D. BOWMAN, OF ALTOONA, PENNSYLVANIA.

CHECK-VALVE.

SPECIFICATION forming part of Letters Patent No. 405,250, dated June 18, 1889.

Application filed November 13, 1888. Serial No. 290,689. (No model.)

To all whom it may concern:

Be it known that we, CHARLES B. DUDLEY and JOHN D. BOWMAN, both of Altoona, county of Blair, State of Pennsylvania, have 5 invented a new and useful Improved Check-Valve, of which the following is a true and exact description, reference being had to the accompanying drawings, which form a part of this specification.

10 Our invention relates to the construction of a check-valve primarily designed for use in connection with the air-brake system of a railway-train; and we have especially designed it for use in the connecting-pipe leading 15 from the air-brake system proper to a carbureting system, through which the compressed air, after being impregnated with hydrocarbon vapor, is led to the burners within the car and utilized for lighting it.

20 The object of our invention is to obtain a check-valve which shall be both sensitive in the sense that it will act promptly in cutting off a reflux action of the air or gas and at the same time be so firmly seated as to greatly 25 diminish the chances of gas escaping backward through the seated valve.

A further object which we have in view is to combine with the check-valve a dust-guard, which will prevent any dust from the 30 air-brake system from passing between the check-valve—a point of great importance where the air is used in a carbureting system.

Reference being now had to the drawings 35 which illustrate a valve constructed in accordance with our invention and in what we believe to be the best method devised by us for this application, Figure 1 is a central sectional elevation of such a valve; and Fig. 2, 40 a plan view thereof, partly in section, on the line $\alpha\alpha$ of Fig. 1.

$A A'$ are respectively the entrance and exit pipes through which the air or gas passes to and from our improved check-valve.

45 B is a casting constituting the main part of the valve-chamber; C, a casting adapted to be secured by bolts $L L$, &c., to the under side of casting B, and constituting a part of the valve-chamber. The third casting J is 50 provided to complete the valve-chamber, this

casting J being essentially a cap made removable to permit of the insertion and withdrawal of the check-valve itself.

B', B⁶, and B⁹ are chambers formed in the casting B.

B² is a passage leading from the chamber B' to a passage C', which, through a continuation C², leads to the chamber C³, formed in the casting C.

B⁴ and B⁸ are respectively an annular 60 flange and cross flanges or webs formed on the bottom of casting B, as shown, so as to come above the chamber C³ when the castings C and B are secured together.

B¹⁰ is a passage connecting with the open 65 spaces lying between webs B⁸ and with the chamber C³, through the perforated plate G and felt washer F. At its upper end this passage B¹⁰ leads into chamber B⁶.

B⁵ is an annular flange or projection surrounding the passage B¹⁰, and extending up into chamber B⁶ above the bottom thereof, marked B¹¹, which serves, when protected by a leather washer, as the seat for the check-valve.

B⁷ is an annular groove formed in the bottom of chamber B⁶ below and outside of the portion B¹¹, on which the valve is seated.

C' is a passage formed in casting C adapted to register, as shown, with the passage B² of 80 casting B; C², a passage leading from passage C' to the main chamber C³, formed in casting C.

C⁴ is a central stud or support projecting upward through the chamber C³ to the same 85 level as that of the annular groove, marked C⁵ in the drawings.

D is a threaded pipe adapted to be screwed into the passage B² and to project into the passage C', as shown, when the castings B and 90 C are secured together. It serves the purpose of insuring the correct alignment of the two passages, and is besides a convenient device for regulating the size of the passage.

E is a washer inserted between the castings B and C to aid in making a tight joint 95 between them.

F is a washer or a disk, of felt or some other material permeable to air, but which will prevent the passage of dust.

55

75

95

100

G is a metal plate of similar size to the washer F and perforated with numerous holes, as shown.

H is a washer, of leather or some similar material, which rests on the seat B¹¹ and extends over the annular groove B⁷.

I is the check-valve, formed, as shown, so as to extend over the annular projection B⁵ and seat itself on the leather washer H over the valve-seat B¹¹ at the bottom of chamber B⁶.

i indicates annular serrations formed in the seat of valve I. I' indicates the stem of valve I; J, a cap arranged to screw into the casting B and form a cover for the chamber B⁶.

15 J' is a projecting hollow boss formed in cap J and serving as a guide to the spindle I' of valve I, and also serving to seat and center the spring K, arranged to hold the valve I to its seat.

20 J² is a passage connecting the top of the hollow boss J' with the chamber B⁶.

B⁸ is a passage leading from chamber B⁶ to chamber B⁹.

The way in which the above-described device is put together is apparent from the drawings. In use the air (or it may be other gas) passes from the pipe A to the chamber B', thence through passages B², C', and C² to the chamber C³. From this chamber it passes through the felt disk F and the perforated metal disk G, which form a diaphragm between the chambers C and the continuation of this chamber formed by the rim and flanges B⁴ B³ B⁸ of casting B. Having traversed this diaphragm and been freed from dust in so doing, the air enters the passage B¹⁰ and presses upward against the check-valve, raising it from its seat and escaping into the chamber B⁶, from whence it passes through passage B⁸ to chamber B⁹, and thence through pipe A' to the point of use or storage. Whenever the pressure in chamber B⁹ exceeds that in chamber B', or approaches it within a predetermined amount regulated by the strength 45 of the spring K, the valve I seats itself on the leather washer H and prevents reflux action.

It has been found very difficult in valves of this kind to prevent the gas or air from escaping backward even when the valve is seated, 50 and to overcome this difficulty we have devised the peculiar seat and formation of the valve already described. Before placing the valve I in the chamber B⁶ we pour into the bottom of chamber B a mixture of glycerine

55 and water, or some similar liquid which will evaporate slowly or not at all, and then place the leather washer H in position. The quantity of glycerine mixture or other liquid should be sufficient to saturate the washer H and fill 60 the annular groove B⁷, over the top of which the outer portions of the washer H extend. In this way we insure that the leather washer H shall always be soft and saturated with the mixture. By using in connection with this 65 saturated washer a valve provided with the serrated bearing-face (such as is indicated at i) we insure the perfect closing of the pas-

sage governed by the valve even where the pressure holding the valve to its seat is very light.

The particular formation and arrangement of the passages leading to and from our improved check-valve are not material to our invention, those shown being designed for the conjoint use of the dust-guard and check-valve, as shown in the drawings, and above described.

Having now described our invention, what we claim as new, and desire to secure by Letters Patent, is—

1. In combination with an air or gas conduit, a check-valve chamber having its entrance-passage situated in its bottom and surrounded by an upwardly-extending annular projection, so as to form an annular chamber 85 to contain liquid, a valve-seat formed on the bottom of said chamber around the upwardly-extending flange, a washer of leather or similar material resting on said seat, and a valve shaped to extend over the annular projection 90 and seat itself on the washer aforesaid, all substantially as and for the purpose specified.

2. In combination with an air or gas conduit, a check-valve chamber having its entrance-passage situated in its bottom and surrounded by an upwardly-extending annular projection, so as to form an annular chamber to contain liquid, a valve-seat formed on the bottom of said chamber around the upwardly-extending flange, an annular groove extending around and below the valve-seat, a washer of leather or similar material resting on said seat and extending over the annular depressed groove, and a valve shaped to extend over the annular projection and seat itself on the washer aforesaid, all substantially as and for the purpose specified.

3. In combination with an air or gas conduit, a check-valve chamber having its entrance-passage situated in its bottom and surrounded by an upwardly-extending annular projection, so as to form an annular chamber to contain liquid, a valve-seat formed on the bottom of said chamber around the upwardly-extending flange, a washer of leather 115 or similar material resting on said seat, and a valve shaped to extend over the annular projection and seat itself on the washer aforesaid, said valve having a bearing-face provided with serrations, all substantially as and for the purpose specified.

4. In combination with an air or gas conduit, a check-valve chamber having its entrance-passage situated in its bottom and surrounded by an upwardly-extending annular projection, so as to form an annular chamber to contain liquid, a valve-seat formed on the bottom of said chamber around the upwardly-extending flange, an annular groove 125 extending around and below the valve-seat, a washer of leather or similar material resting on said seat and extending over the annular depressed grooves, and a valve shaped to extend over the annular projection and seat

itself on the washer aforesaid, said valve having a bearing-face provided with serrations, all substantially as and for the purpose specified.

5 5. In combination with an air or gas conduit, a dust-guard consisting of a disk or washer of felt and a similar disk of perforated metal arranged to support the felt secured across the conduit, and a check-valve 10 situated in the conduit on the exit side of the dust-guard.

6. In combination with an air or gas conduit, a valve-chamber casting B, containing chambers B', B⁶, and B⁹ and having below 15 chamber B⁶ an annular flange B⁴ and webs B³, a casting C, containing a chamber C⁸, and having an annular groove C⁵ and a central support C⁴, passages connecting chamber C⁸ with chambers B' and B⁶ and chamber B⁶ with

20 B⁹, a felt washer G and perforated metal supporting-plate F, clamped between the flange and webs B⁴ B³ B⁸ and the groove and support C⁵ C⁴, a check-valve situated in chamber B⁶, and a cap J, forming a cover to said chamber B⁶, all substantially as and for the purpose specified.

7. In combination with an air or gas conduit, a valve-chamber casting B, containing chambers B', B⁶, and B⁹ and having below

chamber B⁶ an annular flange B⁴ and webs B³, 30 a casting C, containing a chamber C⁸ and having an annular groove C⁵ and a central support C⁴, passages connecting chamber C⁸ with chambers B' and B⁶ and chamber B⁶ with B⁹, a felt washer G and perforated metal supporting-plate F, clamped between the flange and webs B⁴ B³ B⁸ and the groove and support C⁵ C⁴, an annular projection B⁵, extending around the entrance of the passage connecting chamber C⁸ with chamber B⁶, so as to 35 form a chamber at the bottom of chamber B⁶ to contain liquid, a valve-seat formed around flange B⁵, an annular depressed groove extending around said valve-seat, a washer H, covering the valve-seat and extending over 40 the depressed groove, a valve I, formed to extend over the projection B⁵ and seat itself on washer H, a valve-stem I', extending up from said valve, a cap J, having a hollow internal projection J' to support and guide the stem 45 I', and a passage J², leading from chamber B⁶ to the top of the hollow projection, all substantially as and for the purpose specified.
